Witness:
P. J. Darrington

UNITED STATES PATENT OFFICE.

HARRY D. BINKS, OF RIVER FOREST, ILLINOIS.

SPRAY APPLIANCE.

Application filed March 25, 1921. Serial No. 455,545.

To all whom it may concern:

Be it known that I, HARRY D. BINKS, citizen of the United States, residing at River Forest, in the county of Cook and State of Illinois, have invented certain new and useful Improvements in a Spray Appliance; and I do hereby declare the following to be a full, clear, and exact description of the invention, such as will enable others skilled in the art to which it appertains to make and use the same.

My invention relates to spraying appliances of the general class employed for producing liquid sprays, such as the so-called spray nozzles, atomizing nozzles, and oil burner nozzles. In one of its general aspects, my invention aims to provide a simple, durable and inexpensive appliance of this kind so arranged that the part which contains the inlet ports for the spray-producing chamber can readily be withdrawn from the appliance to permit of its being cleaned or for replacing the same.

In another aspect, my invention aims to provide a spraying appliance having a single-spray producing chamber adapted to be fed interchangeably through a number of inlet ports, and to provide simple means for shifting the supply of liquid from one to another of its inlet ports, so as to utilize a fresh port in case the previously used one has become clogged or to utilize a port of a different size if the spraying capacity of the appliance is to be altered. In this connection, my invention also aims to provide simple and effective means for indicating the adjustment thus made.

Furthermore, my invention aims to provide a spraying appliance in which the part which contains at least a portion of the spray-producing chamber can readily be withdrawn for cleaning the same, to provide simple and effective means for holding this part in its normal operative position, and to utilize a simple spring for this latter purpose without subjecting the spring to temperature rises or other conditions which may exist within the appliance and which might deleteriously affect the spring.

Still further and more detailed objects will appear from the following specification and from the accompanying drawing in which—

Fig. 1 is a central and longitudinal section through an appliance embodying my

invention and designed for spraying oil as fuel into a furnace or kiln.

Fig. 2 is a transverse section through the same, taken along the correspondingly numbered line of Fig. 1.

Fig. 3 is a rear elevation of the appliance of Fig. 1 showing the indicating arrangement on the same.

Fig. 4 is a central and longitudinal section through the forward end of another embodiment of my invention, namely a spray nozzle in which the spray producing chamber is formed partly in the stationary head and partly in the rotatable stem.

Fig. 5 is a side elevation of the forward end portion of the stem of the appliance of Fig. 4, showing the slots which serve as ports for connecting the bore of the casing with the spray-producing chamber.

Fig. 6 is an end view of a stem interchangeable with that of Figs. 4 and 5 and having ports all of the same size.

Fig. 7 is a transverse section taken along the correspondingly numbered line of Fig. 4.

In the embodiment of Figs. 1 to 3 inclusive the appliance of my invention includes a tubular casing 1 threaded in one of its rear portions for attachment to a pipe 2 through which liquid under pressure can be admitted to the bore of the casing. The forward end of this tubular casing is closed by a head 3 threaded into the mouth of the casing and having a contracted outlet 4 through which the spray is emitted. Coaxial with this outlet, the head 3 is also bored

out to fit the forward end of a cylindrical stem 5, which stem extends through a stuffing box at the rear of the appliance and is pinned to a handle 6 by means of which the said stem can be rotated. The forward end of the stem 5 is bored out to form a whirling or spray-producing chamber to which liquid can be admitted through any one of three pairs of ports, namely the ports 8, 9 and 10 of Fig. 2. These ports as here

shown are all disposed substantially tangential of the chamber 7 and desirably lead into the said chamber near the rear end of the latter, so that the liquid entering through any of these ports will have a spirally advancing motion imparted to the same before it reaches the head 3 and is forced out through the spray outlet 4. The

ports comprising each of the said pairs are desirably diametrically opposite each other

105

110

with respect to the common axis of the outlet 4 and the stem 5, so that by suitably rotating the stem, any one pair of ports can be brought simultaneously into alignment with a pair of oppositely disposed grooves 11 which extend longitudinally of the appliance and which form enlargements for the bore of the stationary head 3. Thus, with the stem 5 in the position of Figs. 1 10 and 2, liquid will be admitted from the bore of the casing through the grooves 11 and the ports 8 to the spray-producing chamber 7, so that with a given pressure of liquid, both the rate at which the spray 15 is emitted and fineness of the latter will depend on the cross-sectional size of these ports 8. If the other sets of ports (9 and 10) are different in size from the ports 8, the spraying capacity of the appliance can 20 be correspondingly varied by simply rotating the stem 5 until it brings the ports of the desired size into effective alignment with the grooves 11.

To keep the forward end of the stem 5 25 in closely abutting relation to the head 3, I desirably provide suitable spring means and preferably dispose the spring for this purpose outside of the rear of the appliance, so that it will not be affected by high temperatures or other conditions existing within 30 or adjacent to the head of the appliance, and also will not be subjected to any action of the liquid with which the appliance may be used. For this purpose, I am here showing 35 the stuffing box through which the stem 5 extends as comprising a bushing 12 threaded into the rear of the casing 1 and comprising a packing 13 around the stem. Threaded into this bushing are a pair of 40 rods 14 which are threaded at their rear ends into a washer 15. This washer forms a thrust plate for engaging the rear end of a compression spring 16 which bears against a pin 17 extending transversely 45 through the stem 5 and which continuously tends to slide the said stem forward so as to press the tip of the stem against the head 3 of the appliance. Then I am also showing 50 the pin 17 as bent down at one end and tapered to form a pointer 18 moving over a plate 19 on the rear of the casing, this plate being marked to indicate the ports or the corresponding spraying capacity which results from the corresponding 55 rotational position of the stem of the appliance.

By thus using a rotating stem as the inlet-controlling member of my appliance and providing simple means for indicating the adjustment of the latter, I can enable even 60 an inexperienced user to make the desired spraying adjustment of the appliance instantly. Likewise, by simply unscrewing the bushing 12 from the casing, I can enable even an inexperienced user to make the desired spraying adjustment of the appliance 65

instantly. Likewise, by simply unscrewing the bushing 12 from the casing, I can remove the stem 5 with this bushing through the rear of the appliance, thus permitting me to remove any scale deposits from the 70 ports or spraying chamber, or otherwise to clean these parts. Or, if the spraying capacity is to be adjusted to a different range from that afforded by the particular sizes of ports in the stem 5, this stem can easily be 75 exchanged for a similar stem having ports of correspondingly different cross-sections. Or, if the appliance is used for a purpose where no such adjustment as to spraying capacity is needed, but where the liquid is 80 apt to clog the nozzle, I can employ a stem (like that of Fig. 6) having ports which are all of the same size, turning this stem so as to use one after another of the said ports until they clog, and thus reducing the 85 frequency with which the clogging portion of the nozzle needs to be withdrawn for cleaning the same.

Moreover, it will be noted that both the 90 adjusting of the stem for shifting the operative connection from one set of ports to another and the entire withdrawal of the stem are readily effected from the rear of the appliance, so that it is not necessary for the user to have access to the head end of the appliance for either of these purposes. This makes my appliance particularly advantageous where liquid is to be sprayed into a heated furnace or into a gas chamber, neither of which ought to be opened 95 more than is absolutely necessary. For example, in the embodiment of Fig. 1, the manipulating is all done from the rear of the appliance or outside of the inclosing wall 20 through which the appliance extends.

However, while I have heretofore described my invention in a desirable embodiment and have spoken of certain uses of the 100 same, I do not wish to be limited to such uses, nor to the details of construction and arrangement thus disclosed, it being obvious that the same might be modified in many ways without departing from the spirit of my invention or from the appended claims. For example, Fig. 4 shows the forward end 105 of a spraying appliance in which the spray-producing chamber consists partly of a bore 7^a in the head 3 of the appliance and partly of a corresponding bore 7^b in the forward end of the stem 5, and in which the inlet ports consist of slots 20 in the forward end of the stem. In this case, these slots are all of the same cross-section, so that the amount of liquid supplied through any pair 110 of them will be the same with a given pressure, thus adapting the construction to conditions where it is particularly important to overcome a clogging of the appliance without taking the same out of service.

I claim as my invention:—

1. In a spraying appliance, a casing, a head secured to an end of the casing and having an outlet and an axial bore with a pair of diametrically opposed longitudinal grooves each of the latter leading into and throughout the length of the bore and having their inner ends extending through the inner end of the head and opening into the casing interior, and a rotatable stem in the casing having one end fitted in said bore and formed with a chamber opening through the said end and into the outlet and having pairs of lateral parts leading directly into the chamber and adapted to be brought into register with the respective grooves upon rotation of the stem. 55
2. In a spraying appliance, a casing having an outlet and having a pair of spaced opposed longitudinal passages, a rotatable stem having a chamber extending through one end thereof and communicating with the outlet, said stem being disposed in the space between the pair of passages and having pairs of lateral ports leading directly into said chamber and adapted to be brought into register with the respective passages upon rotation of the stem. 60
3. In a spraying appliance, a casing having an outlet, a rotatable stem within the casing having a series of ports, a spray-producing chamber communicating with the ports and through the latter with the casing, an abutment loose on the stem, rods connecting the abutment to the casing, a spring encircling the stem and engaging the abutment at one end, and a pin extending transversely through the stem and against which the opposite end of the spring abuts, one end of the pin being extended to form a pointer to indicate the position of the ports of the stem. 65
4. In a spraying appliance, a casing having an outlet, a rotatable stem within the casing having a series of ports, a spray-producing chamber communicating with the ports and through the latter with the casing, an abutment loose on the stem, means to connect the abutment to the casing, a spring 70
- on the stem having one end engaging the abutment, and a combined indicator and abutment for the opposite end of the spring carried by the stem to maintain the stem under tension in operative relation to the casing. 75
5. In a spraying appliance, a casing having an outlet, a rotatable stem within the casing having a series of ports, a spray-producing chamber communicating with the ports and through the latter with the casing, a spring encircling the stem, means to hold one end of the spring against movement relative to the stem, and a combined indicator and abutment for the opposite end of the spring carried by the stem to maintain the stem under tension in operative relation to the casing. 80
6. In a spraying appliance, a casing having an outlet and having a bore and a pair of spaced opposed elongated longitudinal and approximately parallel passages which latter lead into the bore from the periphery of the latter, and a rotatable stem having an end of approximately uniform diameter rotatably fitted in the bore and having a chamber communicating with the casing outlet and further having lateral ports leading from the chamber and adapted to be brought into register with the respective passages upon rotation of the stem. 85
7. In a spraying appliance, a casing, a head secured to an end of the casing and having an outlet and an axial bore of substantially uniform diameter, with a pair of spaced longitudinal passages formed interiorly of the periphery of the head and which communicate with the bore throughout substantially the length thereof and which lead through the inner end of the head and into the casing, and a rotatable stem having an end of substantially uniform diameter fitted in said bore and having a chamber opening into the outlet and having a pair of lateral ports which lead from the passages directly into the chamber of the stem. 90
- Signed at Chicago, Illinois, March 17th, 95
1921.
